(Continued)*Primary Examiner* — Elizabeth Albert*Assistant Examiner* — Kelley Donnelly(74) *Attorney, Agent, or Firm* — Craig A. Deutsch; Karl Hanson(57) **CLAIM**

I claim, the ornamental design for an earplug tip, as shown and described.

DESCRIPTION

FIG. 1 is a perspective view of an earplug tip, showing my new design,

FIG. 2 is a first side elevation view thereof, the opposite side being a mirror image thereof;

FIG. 3 is a second side elevation view thereof, the opposite side being a mirror image thereof;

FIG. 4 is a top plan view thereof; and,

FIG. 5 is a bottom plan view thereof.

The broken lines are for the purpose of illustrating the environment of the design only and form no part of the claimed design.
